CLOCK

Russell J. Viani, New York, N. Y.

Application August 12, 1949, Serial No. 4,439

Term of patent 14 years

(Cl. D42—7)

To all whom it may concern:

Be it known that I, Russell J. Viani, a citizen of the United States, residing at New York, in the county of Bronx and State of New York, have invented a new, original, and ornamental Design for a Clock, of which the following is a specification, reference being had to the accompanying drawing, forming part thereof.

Fig. 1 is a front elevation of a clock, embodying my new design.

Fig. 2 is an end view of the same.

I claim:

The ornamental design for a clock, substantially as shown.

RUSSELL J. VIANI.
